UNITED STATES PATENT OFFICE.

WILLIAM A. LUCKE, OF NEW YORK, N. Y.

SHEET-TURNER.

1,392,185.

Specification of Letters Patent. Patented Sept. 27, 1921.

Application filed October 21, 1920. Serial No. 418,403.

To all whom it may concern:

Be it known that I, WILLIAM A. LUCKE, a citizen of the United States, and resident of the city of New York, borough of Manhattan, county of New York, and State of New York, have invented a new and Improved Sheet-Turner, of which the following is a full, clear, and exact description.

In connection with sheet music, it is a well appreciated fact that the rendition of a piece of music, is often spoiled, due to the delay incurred in the performer having to turn the sheet.

With this in view, I have devised a sheet turner, more particularly adapted for use in connection with instruments, by means of which it will be possible for the operator to effect a turning of a sheet of music without any delay, and confusion, which has been incident to this procedure before.

A further object of my invention is the construction of a device of this nature, which shall be practically automatic, in operation, in that it will be but necessary for a performer to exert a minimum of effort to effect a turning of the sheet.

A still further object of my invention is the construction of a device of this nature which may be of any size and material, so that the same may lend itself to use in connection with any type of instrument, and at the same time be so simple in construction as to permit of its being retailed at a nominal figure.

A further object of my invention is the construction of a sheet turner, which although primarily intended for use in connection with the turning of sheets of music, is not necessarily limited to this adaptation, in that it may be readily utilized for turning the leaves of a book, or for any other purpose.

Reference is had to the attached sheet of drawings as illustrating one practical embodiment of my invention, and in which—

Figure 1 is a partly fragmentary front view of one form of sheet turner which may be constructed in accordance with my invention.

Fig. 2 is a partly sectional plan view taken along the lines 2—2 of Fig. 1, and

Fig. 3 is an enlarged sectional view taken along the lines 3—3 of Fig. 1.

In these views the reference numeral 5 indicates longitudinally extending bars, suitably spaced from each other, and connected

together by side members 6, so as to provide a space 7.

It is to be appreciated that the framework aforesaid may be of any suitable artistic type, if this is desired, together with being of any optional material and size, according to the necessities of its use, with any particular instrument.

A pair of cross bars 8 are conveniently provided between the upper and lower most pairs of bars 5, and preferably intermediate the extremities of the same. Any suitable number of shafts 9, are rotatably mounted within the cross bars 8, and it is to be noted that the upper ends of the series of shafts mounted between these cross bars in preferably extended outwardly, as has been indicated by the reference numeral 10, the outer end portions of the same projecting downwardly as at 11.

Suitable clips 12, are secured to each of the downwardly extending portions 11, and it will be appreciated that if sheets of paper are secured adjacent their outer edges, one to each of the clips 12, that upon a rotation of one of the shafts 9, that a turning of the sheet will be effected.

To now effect a rotation of each of the shafts, it will be noted, reference being had to Fig. 1, that a spring 13 is conveniently associated with the same, one end of the spring being preferably secured to the cross bars 8, the opposite end thereof being secured to one of the shafts 9, the body portion of such spring being coiled around the shaft 9, thus upon any restraining influence being removed from the shaft, it will be appreciated that the same will automatically rotate, carrying the sheet of paper, which is associated to its clip 12.

To provide means which will serve to prevent a rotation of each of the shafts 9, until it is desired that the same will turn, as will be seen reference being had to Figs. 1 and 2, that a second cross bar 14 may conveniently extend between the lower most of the spaced bars 5, and slidably mounted by this cross bar, and an upper turning portion of the lower most cross bar 8, are a series of plungers 15, each of which is held in a normally projected position by means of springs 16.

It is also to be noted that the outer ends of each of the plungers 15, engage with stops 17 affixed to one of each of the shafts 9. Thus it will be seen that upon the plun-

gers being projected by the springs 16, that a prevention of the turning on the part of the shafts 9 will be accomplished.

A series of crank shafts 18 corresponding in number to the number of shafts 9 provided, are rotatably mounted in the form shown, between the lower most pair of spaced bars 5, and each of these crank shafts may be turned by any suitable means, such 10 as a finger portion 19 extending beyond the forward bar 5. Connecting rods 20 are also suitably interposed between the crank portion of each of the shafts 18, and the inner ends of the plungers 15, so as to provide 15 a connecting medium.

Thus it will be seen that each of the shafts 9 will be normally prevented from rotating, but that these members may be actuated in the manner desired, upon the finger pieces 20 19 being operated to effect a rotation of their associated shaft 18, to permit of a retraction of the connected plunger 15, which will then disengage from the stop 17 against which it abuts, thus permitting of a rotation of the 25 shaft with which said stop is associated.

From the foregoing it will be appreciated that I have constructed a sheet turner which will be practically automatic in operation, in that it will be but necessary to practically 30 touch one of the finger pieces 19 to effect a turning of the sheet, desired, thus permitting the performer to read the characters upon the rear face of the sheet with practically no delay.

35 It will further be seen that a sheet turner constructed in accordance with my invention will be extremely simple in construction, thus permitting of its being placed upon the market at a very low figure.

40 Obviously numerous modifications of structure might readily be resorted to without in the least departing from the spirit of my invention, which I claim as—

1. A sheet turner, including pairs of spaced 45 bars, cross bars extending between said pairs of bars, shafts rotatably mounted within said cross bars, and having their upper ends extending outwardly beyond the same, a spring for each of said shafts, said spring having one of its ends secured thereto, its body encircling the same, and having its opposite

end secured to said cross bars, whereby to effect a turning of said shaft, plungers slidably secured to the second of said cross bars, stops affixed to each of said shafts, and in 55 line with the outer ends of said plungers, and normally engaged thereby, and means for effecting a retraction of said plungers.

2. A sheet turner, including pairs of spaced bars, cross bars extending between said pairs of bars, shafts rotatably mounted within said cross bars, and having their upper ends extending outwardly beyond the same, a spring for each of said shafts, said spring having one of its ends secured thereto, its 60 body encircling the same, and having its opposite end secured to said cross bars, whereby to effect a turning of said shaft, plungers slidably secured to the second of said cross bars, springs for normally projecting 65 said plungers to permit of their engagement with the stop secured to each of said shafts for preventing a rotation of the same, crank shafts rotatably mounted between one of the pairs of bars, and connecting rods extending between said crank shaft and the rear ends of said plungers.

3. A sheet turner, including pairs of spaced bars, cross bars extending between said pairs of bars, shafts rotatably mounted within 70 said cross bars, and having their upper ends extending outwardly beyond the same, a spring for each of said shafts, said spring having one of its ends secured thereto, its body encircling the same, and having its 75 opposite end secured to said cross bars, whereby to effect a turning of said shaft, plungers slidably secured to the second of said cross bars, springs for normally projecting said plungers to permit of their engagement with the stop secured to each of 80 said shafts for preventing a rotation of the same, crank shafts rotatably mounted between one of the pairs of bars, connecting rods extending between said crank shaft and the rear ends of said plungers, said crank 85 shafts being each provided with finger pieces to permit a rotation of the same.

WILLIAM A. LUCKE.
